DESIGN FOR A PLAYING CARD

Alden B. Dow, Midland, Mich.

Application March 6, 1941, Serial No. 99,382

Term of patent 14 years

To all whom it may concern:

Be it known that I, Alden B. Dow, a citizen of the United States, residing at Post Road, in the city of Midland, county of Midland, and State of Michigan, have invented a new, original, and ornamental Design for Playing Cards, of which the following is a specification, reference being had to the accompanying drawing, forming a part thereof.

The figure is a plan view of the back of a playing card, showing my new design.

The face of the card is conventional.

The dominant feature of my design consists in the arrangement in the order of their value of the various poker hand combinations, as shown in the drawing.

I claim:

The ornamental design for a playing card, substantially as shown and described.

ALDEN B. DOW.
